(57) **CLAIM**

We claim the ornamental design for a barrier movement operator housing, as shown and described.

DESCRIPTION

FIG. 1 is a perspective view of a barrier movement operator housing;

FIG. 2 is a front elevational view of the barrier movement operator housing of FIG. 1;

FIG. 3 is a rear elevational view of the barrier movement operator housing of FIG. 1;

FIG. 4 is a side elevational view of the barrier movement operator housing of FIG. 1, the opposite side elevational view being an identical image thereof; and,

FIG. 5 is a bottom plan view of the barrier movement operator housing of FIG. 1.
